UNITED STATES PATENT OFFICE

2,059,390

TRANSPORTATION OF PIPE

Ernest C. Pagel, Chicago, Ill., assignor to Signode
Steel Strapping Company, Chicago, Ill., a cor-
poration of Delaware

Application November 14, 1932, Serial No. 642,554

10 Claims. (Cl. 105—369)

My invention relates to the transportation of pipe.

It is particularly applicable, although not limited to the transportation (loading, shipment and unloading) in open or so-called "gondola" railway cars of corrugated metal pipe.

In the transportation of metal pipe it has heretofore been the practice to assemble the lengths of pipe, on their sides or in prone position, in piles or stacks between stakes located at intervals along each side of the car. The lower ends of the stakes were fitted and anchored in stake pockets permanently attached to the side walls of the car,—sometimes to the inside and sometimes to the outside thereof—and at least at the top, and sometimes between rows or tiers of pipe, opposite stakes were interconnected or tied together by wires or other means to prevent their spreading and bending. The use of stakes is expensive, both in labor and material costs, and does not lend itself to the tight clamping together of the constituents of the load. And, particularly when the stakes are located inside of the car walls (i. e. with cars having inside stake pockets) the available space for the load is materially reduced. The unloading of pipes from between the stakes is slow and expensive because, since the stakes cannot be removed until the load has been reduced to a level at least not much above the upper edges of the sides of the car, the pipes must be individually raised above the level of the stakes before they can be lowered to the ground or unloading platform. Also in the loading operation the majority—if not all—35 of the pipes must be lifted over the tops of the stakes.

One of the objects of my invention is to reduce the labor and material costs incident to the transportation of pipe.

Another object is to provide better bracing and more tight clamping together of the constituents of a load.

Another object is to eliminate the necessity for using stakes to hold the load upon the car or other vehicle.

Another object is to provide a method of loading pipe which affords more space for the load.

Another object is to provide loads of lesser height without decreasing the capacity.

Another object is to provide a load which may be more readily loaded and unloaded.

Another object is to provide a method particularly suited for the transportation of corrugated metal pipe.

Another object is to provide a load and method of loading which is simple and reliable.

Another object is to provide a load and method particularly suited for so-called "paved" pipe; i. e., pipe about half of the circumference of which is coated with asphalt or other protective material.

Other objects and advantages will hereinafter appear.

Several typical examples of loads of pipe and of the steps of the method of assembling and anchoring the load upon an open or "gondola" railway car are illustrated in the accompanying drawings. It is to be understood, however, that the drawings are merely typical examples of what can be done and that my invention is equally applicable to other types of transportation vehicles such, for example, as trucks.

In general, my invention contemplates the use of tensioned flexible metal binders; at least one of which encircles each unit constituting a stack of horizontally laid pipes to bind tightly together the unit constituents, another anchors each unit to the car or other transportation vehicle, and still another may encircle those horizontal rows in which pipes overhang the row beneath.

In the drawings,

Fig. 1 is a perspective of a railway car body of the gondola type draped with binders—both unit encircling and unit anchoring—ready to receive its load of pipe.

Fig. 2 is an enlarged view of a portion of a side wall of the car showing how anchoring binders may be attached to inside stake pockets of conventional type.

Fig. 3 is an enlarged view showing how anchoring binders may be attached to the sides of a car which is not equipped with stake pockets.

Fig. 4 is a perspective of a car body in which one load unit, consisting of smaller diameter pipe sections nested within larger diameter pipe sections, has been assembled and anchored.

Fig. 5 is a transverse section through the car showing the anchored unit of pipe in end elevation.

Fig. 6 shows how pipes constituting a horizontal row, which overhangs the row beneath, may be secured together to form a multiple pipe sub-unit.

Fig. 7 is a perspective of one form of holder which may be used to retain the end overhanging pipes of multiple pipe sub-units, particularly until the unit binders are applied in loading or after the unit binders are cut in unloading, and

Fig. 8 shows an arrangement for preventing relative rotation of nested "paved" pipes.

The car illustrated in Fig. 1 is arranged or draped with binders for the loading of three units or stacks or piles of pipe sections arranged end to end according to the preferred practice of my method. The preferred binder material is flexible, flat, metal strap or ribbon. The seals or joints for interconnecting the ends of the tensioned binder loops and the tools for effecting the desired tension and producing the joints or seals may be of any approved type, several of which are well known.

In preparing the car for the reception of its load of pipe sections, as shown in Fig. 1, the unit encircling binders A are laid transversely across the floor and up and over the opposite sides of the car; the length of each being sufficient to encircle or loop the completed unit and provide sufficient excess for the overlapping required in the production of the joint to render the loop permanent after it has been drawn tight. Inasmuch as I have found that one such binder, of say 2" x .050" steel strap, located approximately midway of the length of each unit is sufficient for ordinary sizes and lengths of pipe sections under usual conditions, and the car is assumed to be loaded with three units, three encircling binders A are shown. The unit encircling binders are flanked on each side by anchoring binders B. Each anchoring binder, which for convenience may consist of two lengths or sections, has its opposite ends firmly attached to the car on opposite sides of the space to be occupied by the associated unit. The two sections forming each anchoring binder should be long enough to reach from the place of attachment at one side of the car and over the associated unit of pipe sections to the point of attachment at the other side of the car, with sufficient excess to enable the free ends to be overlapped, preferably at the top of the unit, for the production of the necessary joint therebetween. These anchoring binders are draped from their points of attachment up and over the sides of the car. After the unit is assembled the free ends of each anchoring binder are brought together, preferably at or near the top of the unit, and after being subjected to the requisite tension the ends are joined. I have found that one such anchoring binder, of say 2" x .050" steel strap, located on each side of the encircling binder about midway therefrom to the end is sufficient for ordinary sizes and lengths of pipe sections under usual conditions. Consequently, since the car is assumed to be loaded with three units, six anchoring binders B are shown. Of course, it is to be understood that the number of encircling and anchoring binders may be varied as different sizes, weights and lengths of pipe sections and more or less severe conditions in transit may require or seem to make desirable.

The car chosen for illustration is provided with inside stake pockets of a commonly encountered type. Cars so equipped are ordinarily to be preferred to those having outside pockets as they are wider. Fig. 2 shows how the opposite ends of anchoring binders may be easily attached to such stake pockets. Thus at each of the opposite pockets, which comprises a bail 5 pivotally attached to and between a pair of hinge plates 6 which are bolted or otherwise fastened to the car side wall, the fixed end of an encircling binder is looped about the bail and made secure thereto by folding the end back upon and uniting it to the body of the strap by a suitable joint 7.

Fig. 3, showing a section through the side wall of a car, illustrates how the ends of anchoring binders may be attached thereto in the event the car is not equipped with stake pockets. Under such conditions a small slot or opening 8 may be made through the car wall immediately below the usual edge or border iron 9. Of course, such openings should be provided in pairs along opposite side walls of the car, each pair receiving the fixed end of an anchoring-binder section. Each fixed end of a binder section is passed through its proper car side wall opening 8 and about the edge iron 9 to form a loop and then laid back upon and united to the body of the strap by a suitable joint 10.

After the car has thus been prepared or draped—either partly or wholly—for the reception of its load, the pipe sections constituting one stack or unit are piled upon and above the car floor in horizontal rows. In those rows within the side walls of the car the pipe sections should preferably be laid in such a way that they fill as completely as possible the available space transversely of the car so that up to the level where the car side walls afford lateral support the pipes are more or less wedged in. Thus below the level of the top edge of the car the pipe sections constituting a unit may be piled directly above each other (as shown in the drawings) or the sections of upper rows may be located in the valleys or gaps between pipes constituting the adjacent lower row or both conditions may obtain, depending upon the diameters of the sections constituting the unit and the relation of the diameters to the width of the car. Thus, in the complete unit illustrated in the drawings the pipe sections constituting the three lower rows C, D and E are within the car side walls and, as shown, when the sections of an upper row rest directly above and upon the sections of a lower row, each row substantially fills the car from side to side.

The pipe sections constituting the row F immediately above row E nest in the valleys between the sections constituting row E. If the desired number of sections constituting each unit is sufficiently small, each subsequent row to the top of the load may be arranged with its sections fitting and wedging into the valleys formed between adjacent sections of the preceding row. In this manner each unit will assume above the sides of the car a triangular shaped cross section, each row containing one less pipe than the row immediately below until finally, if limitations of height or weight, etc. do not prevent, the top row will constitute only one pipe section.

However, when it is necessary or deemed desirable to reduce the height of the load or the units are to contain more sections than this arrangement will accommodate, my method lends itself admirably to the production of wider units by permitting the sections of some rows to overhang the outside or end sections of rows immediately therebelow. By the use of such overhanging sub-units the load may be made generally wider, not only because it need not taper, as is the case where all of the sections of a row nest in the valleys of the next lower row, but it may even overhang the sides and exceed the width of the car. The wider loads—permissible because of the elimination of stakes and the ability to overhang sections—not only reduces the relative height of the load but also often permits shorter loads for equal—or even greater—capacity. And, since freight charges are governed by the length of car used, the shorter

loads requiring less car length, decrease shipping expense.

Figs. 4 and 5 clearly show such an arrangement wherein the outside sections of rows G and I overhang the outside sections of rows F and H.

In order thus to permit the overhang of the outside or end sections of vertically adjacent rows the sections constituting those rows which are to overhang are bound together as sub-units, preferably as shown most clearly in Fig. 6. Thus the sections constituting each row which, when loaded, will include sections overhanging the end sections of the row immediately therebelow are encircled individually by sub-unit binders J. I have found that two such binders, say of $3/4'' \times .035''$ steel strap, each located about two feet from an end of the sub-unit are sufficient for ordinary sizes and lengths of pipe sections under usual conditions.

Such a sub-unit may be assembled as the loading progresses by nesting the sections thereof, except the two outside sections, in the valleys between sections of the immediately preceding or lower row. After this is done the two outside sections 15 and 16 are raised into place in alignment with the intermediate sections and there held by hand or a hoisting crane until the sub-unit binders have been looped thereabout and the loops made permanent by joining or sealing together 20 the overlapping ends. These sub-unit binders ordinarily should not be subjected to sufficient tension to prevent them from being depressed into the valleys between the pipe sections when the sections of the next higher row are laid in 25 those valleys. Ordinarily such tightness or tension as may be produced by hand without the use of tools is sufficient for these sub-unit binders. Under such tension they will not prevent the sections of the succeeding row from tightly wedging or nesting into the valleys between the sections 30 of the lower row and that wedging action, by forcing the binders into the valleys, will render them sufficiently taut firmly to clamp or bind together the constituents of the sub-unit.

Instead of manually or by a crane holding the outside overhanging sections in alignment with the intermediate nested sections until the sub-unit binders are placed, it is possible to use rather stiff metal clips or staples 18, shown in 35 detail in Fig. 7, which may be applied clothespin fashion over the adjacent edges of the outside pipe and the nearest nested pipe in the same row, as shown in Fig. 6. Such clips will hold the outside overhanging pipe sections in 40 proper position until sub-unit binders are applied during the loading operation or after the sub-unit binders are cut during the unloading operation. Or, as an alternative, if the restraining and binding effects of the encircling and 45 anchoring binders together with the weight of the sections piled above any overhanging row are entirely adequate to hold the next-to-the-outside sections in place against the displacing tendencies of overhanging sections supported by or suspended therefrom, the sub-unit binders may be dispensed with and such clips, or other appropriate means, alone may be utilized not only temporarily to anchor the overhanging sections to the adjacent inner sections in the same horizontal row but also to assist in retaining the 50 overhanging sections in place during transit.

After a unit of the desired size is assembled the free ends of the encircling binders A are brought together to form a closed loop about the 55 unit; by appropriate tensioning equipment the

binder is tightened until all of the constituents of the unit are securely wedged and bound together; and then the ends are joined or sealed to render the encircling loop permanent. Next the sections of the anchoring binders B are 6 brought together over the unit; tensioned until the unit is firmly secured to the car; and then the ends joined or sealed together to render each partially encircling anchor loop permanent. A like procedure is followed for the remaining units 10 constituting the desired car-load.

It will be obvious that the preparation of loads according to my method is simple, inexpensive as to materials required and saving in time and labor. It is unnecessary to lift all of the load 15 constituents over stakes which must be substantially as high or higher than the peak of the load; each constituent above the car side walls needs be lifted only so high as its location in the load requires. Unloading is equally simple and 20 saving of time and effort. Preparatory to unloading the unit encircling and anchoring binders are cut but, in the absence of shocks and jars of 25 transit, each unit remains intact until the constituent sections are removed.

Overhanging sections are prevented from falling by the presence of the sub-unit binders and, when it becomes necessary to remove them, the clips heretofore described or other appropriate expedients may be employed temporarily 30 to retain such sections after the sub-unit binders are cut until the time arrives for the sections to be lifted or rolled down from their location in the load. Again it is unnecessary to lift the 35 entire load above the tops of stakes.

Sections of corrugated pipe of different diameters may be assembled into units and shipped nested,—smaller diameter sections within those of larger diameter,—as shown in Figs. 4 and 5. The outside or larger diameter pipes constituting, 40 in effect, the frame or skeleton of each unit are anchored together and to the car as hereinbefore described. The inside or smaller diameter pipes are prevented from longitudinal shifting by the interfitting of the hills and valleys thereof with 45 the valleys and hills of the outside sections. It is unusual that the shocks and jars of transit and switching are sufficiently severe to produce objectionable longitudinal shifting between corrugated pipe sections thus nested, even in the 50 absence of any special precaution to eliminate or restrict relative longitudinal movement.

Fig. 8 shows one arrangement which has been found satisfactory for preventing injury to "paved" pipe sections transported in nested fashion. "Paved" pipe usually has half of its circumference coated inside and outside with asphalt or other protective substance to protect the metal against the wearing action of sand, gravel and other abrasive materials which it may be called 55 upon to convey. In transporting such pipe sections the outside coated surfaces may be separated by interposing thin strips of scrap lumber, straw, corrugated paper and the like between adjacent surfaces while transportation units are 60 being assembled and anchored, as hereinbefore described. The nested sections are arranged so that the uncoated areas are in contact as they lie one within the other. And, to prevent relative rotation occurring in transit from bringing coated 65 areas in contact, the nested sections in the lower contacting uncoated areas may be perforated with one or more small aligning holes and a length of soft wire or other appropriate material 70 threaded therethrough. By twisting together 75

the ends of this wire an effective key for preventing relative rotation is provided.

Having thus illustrated and described the nature and a typical embodiment of my invention, what I claim and desire to secure by United States Letters Patent is as follows:

1. The method of preparing, without the use of stakes, pipe for transport in a vehicle which consists in arranging pipe sections in at least one unit supported by the floor of the vehicle and comprising pipe sections piled flatwise upon each other to a height substantially above the upper edges of the sides of the vehicle, binding together by an encircling tensioned flexible binder the pipe sections constituting the unit, and anchoring the unit to the vehicle by another tensioned flexible binder which partially encircles the unit and is secured to the vehicle.
2. The method of preparing, without the use of stakes, pipe for transport in a vehicle which consists in piling sections of pipe flatwise upon each other upon the floor of the vehicle to form a load unit extending to a substantial height above the level of the top edges of the sides of the vehicle, encircling the unit with a tensioned flexible binder which is free from the vehicle, and securing the unit against movement relative to the vehicle by a tensioned flexible anchoring binder which partially encircles the unit and is attached to the vehicle.
3. The method of preparing, without the use of stakes, pipe for transport in a vehicle which consists in arranging the sections of pipe lengthwise of the vehicle and horizontally in superposed rows to form a load unit extending a substantial height above the upper edges of the sides of the vehicle, an outside pipe section of at least one row overhanging an outside pipe section of the row therebelow, encircling only the row having the overhanging pipe section with a tensioned flexible sub-unit binder, encircling the unit with a tensioned flexible binder to hold together the constituents of the unit, and anchoring the unit to the vehicle by a binder which at least partially encircles the unit and is secured to the vehicle.
4. The method of preparing a unit of pipe sections for shipment in a gondola car, without the use of stakes, which consists in placing a flexible metallic unit-encircling binder across the floor and up opposite side walls of the car, anchoring to opposite sides of the car one end of each of at least two flexible metallic unit-anchoring binder sections, piling, to a height substantially higher than the top edges of the car sides, pipe sections upon the floor of the car over the unit-encircling binder draped thereacross, bringing together the ends of the unit-encircling binder to form a loop about the pile of pipe sections, tensioning the unit-encircling binder and uniting the ends to make the tensioned loop permanent, bringing together in pairs the free ends of the unit-anchoring binder sections to form a complete unit-anchoring binder, and tensioning each unit-anchoring binder upon the pile of pipe sections and uniting the ends to complete each unit-anchoring binder.
5. The method of preparing a unit of pipe sections for shipment in a gondola car, without the use of stakes, which consists in placing a flexible metallic unit-encircling binder across the floor and up opposite side walls of the car, anchoring to opposite sides of the car one end of each of at least two flexible metallic unit-anchoring binder sections, piling, to a height substantially above the top edges of the car sides, pipe sections

upon the floor of the car over the unit-encircling binder draped thereacross, the pipe sections being piled flatwise in superposed horizontal rows with an outside pipe section of at least one row overhanging an outside pipe section of the row therebelow, encircling with a tensioned flexible sub-unit metallic binder only the row having the overhanging pipe section, bringing together the ends of the unit-encircling binder to form a loop about the pile of pipe sections, tensioning the unit-encircling binder and uniting the ends to make the tensioned loop permanent, bringing together in pairs the free ends of the unit-anchoring binder sections to form a complete unit-anchoring binder over the top of the pile of pipe sections, and tensioning the unit-anchoring binder upon the pile of pipe sections and uniting the ends thereof.

6. The method of preparing a unit of pipe sections for shipment in a vehicle, without the use of stakes, which consists in piling flatwise in superposed horizontal rows from the floor of the vehicle to a height substantially above the top edges of the vehicle sides, sections of pipe to form a load unit, an outside pipe section of at least one row above the level of the top edges of the sides of the vehicle overhanging an outside pipe section of the adjacent row therebelow, anchoring such overhanging section to another section in the same row, completely encircling the entire unit with a tensioned flexible binder to hold together the constituents of the unit, and anchoring the unit to the vehicle by a tensioned flexible binder which at least partially encircles the unit and is secured to the vehicle.

7. The method of preparing a unit of pipe sections for shipment in a vehicle, without the use of stakes, which consists in piling flatwise in superposed horizontal rows from the floor of the vehicle to a height substantially above the level of the top edges of the vehicle, sections of pipe to form a load unit, an outside pipe section of at least one row located at a level higher than the top edges of the sides of the vehicle overhanging an outside pipe section of the adjacent row therebelow, temporarily anchoring such overhanging section to another section, completely encircling only the row having the overhanging pipe section with a tensioned flexible sub-unit binder to form a load sub-unit of such row, completely encircling the entire unit with a tensioned flexible binder to hold together the constituents of the unit, and anchoring the unit to the vehicle by a tensioned flexible binder which at least partially encircles the unit and is secured to the vehicle.

8. A load unit for transport in a vehicle, without the use of stakes, comprising a plurality of pipe sections piled in horizontally superposed rows to a height substantially above the level of the top edges of the side walls of the vehicle, a tensioned flexible binder completely encircling the pile of sections to secure the same together, and a tensioned flexible anchoring binder at least partially encircling the pile of sections and attaching the same to the vehicle, each of said binders being independent of the other.

9. A load unit for transport in a vehicle, without the use of stakes, comprising a plurality of pipe sections piled together in superposed rows to a height substantially above the level of the top edges of the side walls of the vehicle, the sections of each higher row nesting in the valleys between sections constituting the row therebelow and at least one row higher than the top edges of

the side walls of the vehicle including a section overhanging an outside section of the row therebelow, a tensioned flexible sub-unit binder encircling and holding together the sections constituting the row including the overhanging section, and a tensioned flexible binder completely encircling the entire pile of sections to hold together the constituents thereof, each of said binders being independent of the other.

10 10. A load unit for transport in a vehicle, without the use of stakes, comprising a plurality of pipe sections piled together in superposed and interfitting horizontal rows to a height substantially above the level of the top edges of the

sides of the vehicle, one of the pipe sections of at least one row which is at a level above the top edges of the sides of the vehicle overhanging an outside section of a row therebelow, a tensioned flexible sub-unit binder encircling only 5 and holding together the sections constituting the row including the overhanging section, a tensioned flexible binder completely encircling the entire pile of sections to hold together the constituents thereof, and a flexible tensioned anchoring binder for securing the pile of sections to the vehicle, each of said binders being independent of the other.

ERNEST C. PAGEL.
